UNITED STATES PATENT OFFICE.

JAMES C. O'NEIL, OF CLEVELAND, OHIO.

ELECTRIC SIGNALING DEVICE.

SPECIFICATION forming part of Letters Patent No. 406,057, dated July 2, 1889.

Application filed September 29, 1888. Serial No. 286,770. (No model.)

To all whom it may concern:

Be it known that I, JAMES C. O'NEIL, of Cleveland, in the county of Cuyahoga and State of Ohio, have invented certain new and useful Improvements in Electric Signaling Devices; and I do hereby declare the following to be a full, clear, and exact description of the invention, such as will enable others skilled in the art to which it pertains to make and use the same.

My invention relates to improvements in electric signaling devices for railways; and it consists in certain features of construction and in combination of parts hereinafter described, and pointed out in the claims.

In the accompanying drawing, the figure is a plan showing in diagram the different circuits used.

A represents a single-track railway, and A' A' outposts supposed to be located some distance on either side of a crossing at A'. Wires a a' extend from one outpost to the other, the ends of these wires being normally separated, but are closed by means of circuit-closers located at a² and operated by the passing train. A variety of circuit-closers suitable for the purpose are well known, and about any such device whereby the circuit is momentarily closed by the passing train will answer the purpose. Wires a a' do not directly include a battery, and these wires are of course only closed one at a time by means aforesaid. The battery B is connected from the one pole thereof by means of wire b with wire a, wire b having in circuit magnet C. Wire b' connects the other pole of the battery with wire a'. With such construction, whenever wires a a' are connected at either end thereof, a closed circuit is established having in circuit battery B and magnet C.

C' is an armature that is operated by magnets C, this armature being attached to lever C². This lever is pivoted at c and has a hook end or toe c', and at the other extreme has an attachment or stop c². By means of spring c³ the armature is held separated from the cores of the magnets, except when an electric current is passed through the magnets to attract the armature.

Shafts D and E are each members of the same clock-work, the former revolving some-

what rapidly and the latter shaft being regulated to move at the desired slow speed. Shaft D is provided with a lateral pin d, the ends of which are engaged by stops c² whenever the armature is in its elevated position, such engagement of stop and pin causing the clock-work to stop instantly. On shaft E are mounted wheels E' and E², the former having notch e' and the latter having notch e². Notch e' receives toe c', and thereby allows the opposite end of the lever to be elevated far enough to bring stop c³ in contact with the end of pin d, whereby the clock-work is stopped, as aforesaid. Whenever the circuit is closed at either outpost A', armature C' is depressed and the clock-work is set in motion, and an instant later notch e' has passed from under toe c', after which the toe rides on the periphery of the wheel, during which stop c² cannot engage pin d, in consequence of which the clock-work (in case, as shown, of but one notch e') must run while wheel E' is making a revolution. On the right hand in the drawing is shown another clock-work, that may be the fac-simile of the one just described, except that wheel F, corresponding with wheel E² of the opposite clock-work just described, has a projecting lug f, instead of a depression e². Opposite lug f, and connecting therewith, is the contact-point of spring g, this spring being connected by wire G with spring g'. The contact-point of the latter is located opposite notch e², so as not to come in contact with wheel E² when the latter is at rest in the normal position shown.

Wires h and h' connect with the respective poles of battery B, and lead from thence and electrically connect, for instance, with shafts E and F, or with other parts of the respective clock-works, wire h including the electric signal or bell H. Wires i and i' connect with the respective poles of battery B and lead from thence to circuit-closer I, located at or near the crossing, so that this circuit is closed at this point by train passing the crossing in either direction. Wire i includes magnet J, the latter having a co-operating armature J', all substantially as heretofore described.

In operating the device a train approaching from either direction will cause the main circuit to be closed as the train passes the

outpost, thus establishing an electric current through wires *a b b' a'*, by means of which magnets *C* attract armature *C'*, causing the latter to descend, whereby the clock-work at 5 the left hand is released and set in motion, the immediate effect of which is to cause spring *g'* to engage the periphery of wheel *E'*, and thus establish a short circuit that includes the signal, which latter is consequently 10 sounded, and as toe *c'* cannot enter notch *e'* until wheel *E'* has made a revolution the signal continues to sound until such time as the clock-work is stopped by means aforesaid, the relation of parts being such that when this 15 occurs the point of spring *g'* will be opposite notch *e'*, with the short circuit broken and with the parts at the place of beginning and ready for another signal, the train meantime having presumably passed or made its near 20 approach to the crossing, so that the signal for such train is no longer needed. Now, if no interposing mechanism were provided, the signal would sound again as the outgoing train passed the other outpost, and teams 25 would likely wait at the crossing, hearing the signal and hearing the train, but not knowing that the train was speeding away in the distance instead of approaching the crossing. With the construction shown, as the train 30 passes in the vicinity of the crossing and engages circuit-closer *I*, the circuit of wires *i i'* is closed, this circuit including battery *B* and magnet *J*, whereupon the clock-work at the right hand is set in motion, the immediate 35 effect of which is to turn lug *f* away from its engagement with spring *g*, and thus break the short circuit that alone can operate the signal. This short or signal circuit of course remains unbroken while wheel *F* is making a 40 revolution—a time supposed to be ample for the passage of the train beyond the outpost. To recapitulate, a train approaching the crossing from either direction causes the signal to sound; but the same train at or near the crossing cuts out the signal device, so that it cannot sound while the train is passing away 45 from the crossing.

The clock-work may be varied indefinitely. When attendance is convenient a clock-work 50 that requires winding every day would not be seriously objectionable. In other places an eight-day clock-work, or one that would require winding not oftener than once a month, might be desirable. Also, the notched wheels, 55 for instance wheels *E'* and *E²*, in place of having one notch each, as shown, may have two or more notches each, if preferred, the speed of the wheel being regulated accordingly, so that a suitable time will elapse for sounding 60 the signal while the wheels are passing the distance from one notch to another.

To avoid any possible confusion in tracing the different circuits I will state that the short or signal circuit consists of wires *h h'* and *G*, springs *g g'*, and such intervening portions 65 of the respective clock-works as the electric current follows in passing from wire *h* to spring *g'*, and from spring *g* to wire *h'*, or vice versa.

Various modifications will be readily suggested to electricians. For instance, wheel *E²*, instead of having notch *e²*, may have an insulating-block inserted at this point, which would answer the same purpose; also, wheel *F* might have an insulating-surface except at 75 contact-point *f*, if so preferred.

What I claim is—

1. In a railroad-signal, the combination, with circuit-closers located in proximity to and on opposite sides of a crossing, a metallic circuit including both of said circuit-closers, and a battery, of an electro-magnet in circuit with either of said circuit-closers, an armature, a mechanically-driven circuit-closer controlled by said magnet, a mechanically-driven circuit-breaker, an electro-magnet for controlling the same, a circuit including the mechanically-driven circuit closer and breaker, the battery and an alarm, a track circuit-closer at the crossing, and a circuit including the latter-named circuit-closer, the battery and electro-magnet of the mechanically-driven circuit-breaker, substantially as set forth.

2. In a railroad-signal, the combination, with electric circuits adapted to be made and broken by a passing train, electro-magnets, and armature-lever carrying armature, of mechanically-driven motors, a revolute circuit-closer comprising two disks carried by a shaft of one of said motors, one of said disks being provided with a notch for the reception of one end of an armature-lever, and the other disk having a notch for the accommodation of a contact-spring, a revolute circuit-breaker carried by a shaft of the other motor and comprising two disks, one of said disks having a notch for the reception of the end of an armature-lever, and a projection on the other disk to engage a contact-spring, and a circuit including both the revolute circuit closer and breaker, the battery, and a signal, substantially as set forth.

In testimony whereof I sign this specification, in the presence of two witnesses, this 23d day of August, 1888.

JAMES C. O'NEIL.
